UNITED STATES PATENT OFFICE

ALEXANDER SPENCER AND RICHARD THOMSON GLASCODINE, OF LONDON, ENGLAND

CENTRAL BUFFING AND DRAW-GEAR

Application filed October 22, 1929, Serial No. 401,517, and in Great Britain September 12, 1929.

This invention relates to central buffing and draw gear for automatic couplings.

The object of the invention is to provide simple and efficient gear comprising double acting buffing and draw springs each constituted by a column of suitable india-rubber spring units. These units may be of the well-known kind embodying concentric india-rubber rings or frames moulded on to metal plates, the several units of the column constituting the spring being separated from each other by metal dividing plates. Associated with these india-rubber springs, which are embraced by the draw bar yoke, are buffing springs, also it may be of india-rubber of the said type, located at the front of the headstock and which are compressed upon inward movement of the coupler head by means of a movable compression member or casting against which a striking face at the rear of the coupler head is adapted to bear. The springs embraced by the yoke are in part compressed before the external buffing springs come into action.

The india-rubber springs within the yoke may be mounted on an axial bolt which maintains them at all time in their proper central position within the yoke.

Furthermore the invention has for its object to provide compact and satisfactory means for carrying the coupler head on a platform or bar supported by swinging links in order to centralize the same.

According to the invention the swinging links are carried by the compression member or casting inward movement of which effects the compression of the external buffing springs, and preferably the said swinging links and supporting platform or bar are located between the external buffing springs.

In order to provide the double spring action the springs embraced by the yoke are arranged between the follower head and a compression plate and between the end of the yoke and a second compression plate, respectively. These compression plates are provided with projecting lugs or wings the ends of which abut against the end of the yoke, or a plate which bears on the end of the yoke, and the follower head respectively,

the arrangement being such that both the springs are simultaneously but independently compressed upon both buffing and drawing.

The accompanying drawings illustrate a construction of central buffing and draw gear embodying the invention.

Figs. 1 and 2 show the gear in sectional elevation and sectional plan respectively;

Fig. 3 is a sectional end elevation thereof;

Figs. 4 and 5 are sections corresponding to the line A B and C D respectively of Fig. 3, and

Fig. 6, as regards its right hand half, is a cross-section corresponding to the line E F of Fig. 1, and as regards its left-hand half is a cross-section corresponding to the line G H of Fig. 1.

The shank 1 of the coupler head 2 is connected in the usual manner by a pivot pin 3 to the front follower head 4 or to a knuckle 5 centered on said follower head. Supporting cotters 6 and 7 pass through slots formed therefor in the shank 1 and follower head 4 respectively, and through slots in the draw bar yoke 8, the end portions of said cotters sliding in slots 9 formed in brackets 10 which are fixed to the adjacent longitudinal members 11 of the underframe.

Embraced by the yoke 8 are two multiple unit india-rubber springs 12 and 13. The spring 12 is arranged between the follower head 4 and a compression plate 14, and the spring 13 is arranged between a plate 15 located between it and the end 16 of the yoke, and a second compression plate 17.

The compression plate 14 is formed with rearwardly extending wings 18 that embrace the rear spring 13 and the rear ends of which engage recesses in the plate 15 that bears on the end 16 of the yoke. In like manner the compression plate 14 is formed with forwardly extending wings 19 that embrace the forward spring 12 and the forward ends of which engage recesses in the follower head 4. The arrangement is such that upon either buffing or drawing both the springs are compressed, the compression plates being moved away from each other, thereby giving a double acting spring

action in both buffing and drawing. The wings 18 and 19 of the compression plates 14 and 17 are held firmly against any tendency to spread apart by their ends en- 5 gaging the recesses in the plate 15 and the follower head 4 respectively.

Preferably, as shown, the india-rubber springs 12 and 13 are of the well-known type comprising units arranged in column 10 form with metal separating plates between the several units, each unit consisting of a number of concentric rings or frames of india-rubber moulded on to and projecting from each side of a metal plate, the rubber 15 at one side of the plate being connected to the rubber at the other side thereof by rubber that extends through holes in the said plate. The spring units and metal dividing plates are mounted on an axial bolt 20, 20 screwed at its front end into the follower head 4 and, at its rear end, passing through the plate 15 and the end 16 of the yoke and being fitted with a retaining nut 21. The axial bolt 20 of course also extends through 25 central holes formed therefor in the compression plates 14 and 17. The fixed abutment 22 for the end of the yoke is formed with a recess 23 to receive the rear end of the bolt 20 and its nut 21.

30 Arranged at the outer side of the headstock are two india-rubber buffing springs 24 located one at each side of the coupler head shank 1 and compressed upon inward movement of the coupler head 2 by the 35 bearing of a striking face at the rear of the coupler head on a casting 25 arranged in front of the said springs 24. The casting 25 is formed, midway of its length, with a hole through which the shank 1 of the 40 coupler head extends and with rearwardly extending annular flanges 26 that surround the springs 24 and slide between guiding and supporting webs 27 that project forwardly from a casting 28 fixed to the vehicle 45 headstock. Each external buffing spring is an india-rubber spring of the type before-mentioned, namely comprising concentric india-rubber rings moulded on to a metal plate, and the said spring is mounted on a 50 bolt passed through the front casting, axially through the spring and through a hole formed therefor in the casting fixed to the vehicle headstock.

The coupler head 2 and shank 1 are sup- 55 ported on a centralizer platform or bar 30 having hook-like ends 31 supported on pins 32 carried by the lower ends of swinging links 33 the upper ends of which are mounted to rock on pins 34 mounted in the 60 front casting 25. As will be seen the swinging centralizing links 33 are located between the front buffer springs 24 and the coupler head shank 1.

To enable the parts to be assembled, the 65 front casting 25 is formed with a lateral

opening 35 through which the platform or bar 30 can be slid into position. Furthermore the hole in the front casting 25 through which the coupler head shank 1 is passed is enlarged at its upper part to 70 allow of the said shank being passed therethrough and after this has been done the said enlargement is filled in by a block 36 which is fixed in place as by screws 37. As usual the centralizing platform or bar 30 is 75 formed with upwardly extending lugs 38 between which the coupler head shank 1 is seated. The face 39 of the front casting 25 upon which bears the striking face 40 at the rear of the coupler head 2 is suitably curved as shown.

It will be appreciated that the buffing and draw spring arrangement according to the invention is highly efficient, compact, and of sturdy construction.

The various parts are so designated as to be readily assembled and the provision of the external buffing springs in combination with the buffing and draw springs within the yoke provides a buffing spring arrangement well adapted to absorb and cushion 90 severe blows and buffing shocks.

Outside buffing springs and a centralizing device as hereinbefore described may be used with spring arrangements within the yoke other than those shown, or with a friction draft gear within the yoke, without departure from the invention.

Moreover, it is within the scope of the invention to employ the arrangement described of double acting buffing and draw springs within the yoke in association with another arrangement of outside buffer, if desired, or even without the provision of an outside buffer. Furthermore the double 100 acting springs within the yoke may be duplicated or in some cases three sets of such 105 springs may be employed.

Finally the invention is not restricted to any details of construction described with reference to the example illustrated as variations may be made as may be found necessary or desirable in practice.

What we claim is:—

1. In central buffing and draw gear, a 115 coupler head having a shank, india-rubber buffing springs located in front of the vehicle headstock, a movable member for compressing said front buffer springs upon inward movement of said coupler head, and means, 120 carried by said movable member, for centralizing said buffer head.

2. In central buffing and draw gear, a 125 coupler head having a shank, two india-rubber buffing springs located in front of the vehicle headstock one at each side of the shank of said coupler head, an endways movable member located in front of said springs and against which said coupler head bears when moved inwardly, a cross bar

which supports said coupler head and its shank, links that carry the said cross bar, and pins from which said links are suspended mounted in the said movable member.

3. In central buffing and draw gear, a coupler head having a shank, two india-rubber buffing springs located in front of the vehicle headstock one at each side of the shank of said coupler head, an endways movable member located in front of said springs and against which said coupler head bears when moved inwardly, a supporting guide for said movable member fixed to the vehicle headstock, a cross bar which supports said coupler head and its shank, links located one at each side of the shank of said coupler head that carry the said cross bar, and pins from which said links are suspended mounted in the said movable member.

4. In central buffing and draw gear, a coupler head having a shank, two india-rubber buffing springs located in front of the vehicle headstock one at each side of the shank of said coupler head, an endways movable member located in front of said springs and against which said coupler head bears when moved inwardly, a supporting guide for said movable member fixed to the vehicle headstock, bolts carried by said movable member and said supporting guide on which said front springs are mounted, links that carry the said cross bar, and pins from which said links are suspended mounted in the said movable member.

In testimony whereof we affix our signatures.

ALEXANDER SPENCER.
RICHARD THOMSON GLASCODINE.
